Primary Examiner—Stella M Reid*Assistant Examiner*—Mark A Goodwin(74) *Attorney, Agent, or Firm*—Porter, Wright, Morris & Arthur, LLP(57) **CLAIM**

The ornamental design for a tray with multiple separate spaces for plant pots, as shown and described.

DESCRIPTION

FIG. 1 is a perspective view of a tray with multiple separate spaces for plant pots showing my new design;

FIG. 2 is a front elevational view thereof, the rear elevational view being a mirror image thereof;

FIG. 3 is a left side elevational view thereof, the right side elevational view being a mirror image thereof;

FIG. 4 is a top plan view thereof; and,

FIG. 5 is a bottom plan view thereof.
